CLAIM

The ornamental design for a combined sofa, chairs and table set as shown and described.

DESCRIPTION

FIG. 1 is a front, right and top perspective view of the table component of the combined sofa, chairs and table set of FIG. 25, shown separately to reveal aspects of the design that may not be apparent in other views;

FIG. 2 is a rear, left and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front, right and top perspective view of one of the two chair components of the combined sofa, chairs and table set of FIG. 25, shown separately to reveal aspects of the design that may not be apparent in other views;

FIG. 10 is a rear, left and bottom perspective view thereof;

FIG. 11 is a front elevation view thereof;

FIG. 12 is a rear elevation view thereof;

FIG. 13 is a left side elevation view thereof;

FIG. 14 is a right side elevation view thereof;

FIG. 15 is a top plan view of thereof;

FIG. 16 is a bottom plan view of thereof;

FIG. 17 is a front, left and top perspective view of the sofa component of the combined sofa, chairs and table set of FIG. 25, shown separately to reveal aspects of the design that may not be apparent in other views;

FIG. 18 is a front, right and bottom perspective view thereof;
 FIG. 19 is a front elevation view thereof;
 FIG. 20 is a rear elevation view thereof;
 FIG. 21 is a left side elevation view thereof;
 FIG. 22 is a right side elevation view thereof;
 FIG. 23 is a top plan view thereof;
 FIG. 24 is a bottom plan view thereof; and,
 FIG. 25 is a top perspective view of a combined sofa, chairs and table set showing our design.

The broken lines shown in the figures depict portions of the combined sofa, chairs and table set, that form no part of the claimed design.
